DESIGN FOR A SET OF GAME PIECES

Bert J. Bratt, Chicago, Ill.

Application December 29, 1938, Serial No. 82,041

Term of patent 3½ years

To all whom it may concern:

Be it known that I, Bert J. Bratt, a citizen of the United States, residing at Chicago, in the county of Cook and State of Illinois, have invented a new, original, and ornamental Design for a Set of Game Pieces, of which the following is a specification, reference being had to the accompanying drawings, forming a part thereof.

Figures 1, 2, 3, 4, 5, 6, 7, 8, 9, 10, 11, 12, 13, are side elevational views of the various game pieces of the set constituting my new design; and

Figures 1^a, 2^a, 3^a, 4^a, 5^a, 6^a, 7^a, 8^a, 9^a, 10^a, 11^a, 12^a, 13^a, are plan views respectively of the pieces shown in Figures 1, 2, 3, 4, 5, 6, 7, 8, 9, 10, 11, 12, 13.

I claim:

The ornamental design for a set of game pieces, substantially as shown.

BERT J. BRATT.
